UNITED STATES PATENT OFFICE.

TOMEZO IMAOKA, OF KITAKU, OSAKA CITY, JAPAN.

PUMP DREDGER OR SUCTION DREDGER.

Application filed November 6, 1922. Serial No. 599,455.

To all whom it may concern:

Be it known that I, TOMEZO IMAOKA, subject of the Emperor of Japan, residing at No. 10, Naruomachi, Kitaku, Osaka City, 5 Japan, have invented certain new and useful Improvements in Pump Dredgers or Suction Dredgers, of which the following is a specification.

This invention relates to improvements in 10 pump dredger or suction dredger.

The pontoon has two rods to be stucked up the sea bottom during the dredging operation and pulled out alternately. One rod is positioned on the axial line of the pontoon 15 and is called the central rod and another is situated on a line inclined 45° to the axial line and is called the advancing rod.

The pontoon is turned 90° in one and opposite direction about the central rod and 20 the advancing rod alternately performing dredging operation during its turning about the rods.

The object is to advance the pontoon along a straight line dredging a boundary 25 having a definite width, by which a fixed delivery spout may be used instead of the flexible one necessary in the pump dredger hitherto used.

Fig. 1 is a side elevation of the dredger. 30 Fig. 2 is a top plan view of the dredge.

Fig. 3 is a geometrical figure to explain the action of dredger.

Fig. 4 is a diagram showing the positions and course of the pontoon in practical use.

The pontoon of pump dredger or suction dredger hitherto used can scarcely advance in a definite direction, consequently the boundary of the dredged area is very irregular. This invention is contrived to 40 eliminate this defect and its essential feature is to advance the pontoon in a definite direction performing dredging operation, by which a straight boundary having a definite width can be dredged regularly and the delivery spout may be fixed in a desired position.

In the drawings *a* designates the pontoon and *b* the main pump. *c* is the suction pipe and *d* is the delivery pipe. The suction pipe 50 has its bottom end connected pivotally in such a way that the inlet may be turned in a plane perpendicular to the axial line of the pontoon in accordance with the tide or the depth of the sea bottom to be dredged. By 55 this construction the inlet of the suction

pipe may be faced to the inclined surface to be dredged and the dredged trace marked by the turning movement of the pontoon will be a circular curve approximately.

The delivery pipe is provided with a turn-table joint *e* in the straight line of the central rod *i* and is connected to the horizontal branch *g* by the vertical pipe *f*. The mud or sand dredged is delivered to the spout *r* from the outlet of the delivery pipe *h* connected to the branch pipe *g*. *i* is the central rod situated on the axial line of the pontoon and this rod *i* is to be forced into the sea bottom during a dredging operation and the pontoon is to be turned 90° about 70 this rod *i*.

When the pontoon turns 90°, one dredging operation is ended. Then the advancing rod *j* is positioned on a line inclined 45° to the axial line, is forced into the sea bottom, and the central rod *i* is pulled out and then the pontoon is to be turned 90° in the opposite direction about the advancing rod *j* performing the next dredging operation.

The distance the pontoon is to be advanced per dredging operation depends upon the nature of the mud or sand to be dredged and the distance may be adjusted by changing the relative positions of the advancing rod *j* to the central rod *i*. For this purpose, the beam *k* is provided along the line inclined 45° to the axial line and the advancing rod may change its position along the beam *k*.

The reason why the pontoon takes a definite course is illustrated geometrically in Fig. 3.

When the pontoon *a* is in the position shown by the full lines, the central rod is 95 in the position shown by *C*, the inlet of the suction pipe at the point *S* and the outlet of the delivery pipe at the point *D*.

If the pontoon is moved to the position shown by the dotted line turning 90° about 100 the central rod at *C*, the inlet of the suction pipe will be moved to the point *S'*.

At this time the central rod is pulled out and the advancing rod at the point *R* is inserted and then the pontoon is turned in opposite direction about the advancing rod at *R*. When it turns 90° the inlet of the suction pipe will be moved to the point *S''*.

Nextly the advancing rod is to be pulled out and the central rod at the point *C'* is in 110

serted and the pontoon is turned about the central rod at C' and so on.

In the triangles $CS'R$ and $C'S''R$
 $CS'=C'S''$ $S'R=S''R$ $CR=C'R$,
5 therefore these triangles are similar and the angles $S''C'R$ and $S'CR$ are similar.

As the angles $RC'C$ and RCD are 45° ,
 $\angle S''C'R + \angle RC'C = \angle S'CR + \angle RCD = 180^\circ$.

10 By the above reason, CC' and SS'' are on a straight line, consequently it must be clear that the pontoon advances along a definite straight line.

AB is a distance which the delivery end 15 D moves on the right and left during the pontoon advances along the course CC' .

$$CR=CC' \sin 45^\circ = 0.707 CC'$$

$$AB=CR (1-\sin 45^\circ) = 0.207 CC'$$

Such small movement of the outlet may 20 be made up by increasing a little the width of the delivery spout r or by a flexible joint of the delivery pipe with the spout.

In the practical use of this dredger it is 25 convenient to position the pontoon firstly on the position o shown in Fig. 4 and to dredge the boundary having the width p . When the pontoon completes a desired course, it is to be moved to the position q , the opposite side of the delivery spout r , 30 and repeat the dredging operation.

The final operation is the moving of the pontoon to the position s and the dredging of the mud or sand laying under the spout r .

Thus a wide boundary may be dredged,

fixing the delivery spout in a desired position. 35

Having now particularly described and ascertained the nature of my said invention, and in what manner the same is to be performed, I declare that what I claim is— 40

The combination with a pump dredge, of means whereby said dredge may be advanced along a straight line whereby a dredging operation of uniform width may take place, said means comprising a vertically disposed member slidably mounted in an opening of the dredge adjacent one end thereof and in the plane of the longitudinal axis of the dredge and adapted to be imbedded in the bottom of a body of water, a 45 second vertically disposed member, said second member being adapted to be received in any of a plurality of apertures disposed at right angles to each other and having their center apertures positioned for the reception of the first mentioned vertically disposed member, said crossed plurality of apertures being equidistant from the aperture in which the first mentioned member is disposed and equidistant from the longitudinal axis of the dredge. 50

55 In testimony whereof I affix my signature in presence of two witnesses.

TOMEZO IMAOKA.
